US00D787107S

(12) **United States Design Patent** (10) Patent No.: **US D787,107 S**
Burmeister et al. (45) Date of Patent: **** May 16, 2017**

(54) **LED MODULE**

- (71) Applicants: **Jens Burmeister**, Eberbach (DE);
Bernd Schwarz, Eberbach (DE)
- (72) Inventors: **Jens Burmeister**, Eberbach (DE);
Bernd Schwarz, Eberbach (DE)
- (73) Assignee: **COOPER CROUSE-HINDS GMBH**,
Soest (DE)
- (**) Term: **15 Years**
- (21) Appl. No.: **29/551,240**
- (22) Filed: **Jan. 12, 2016**
